(57) **CLAIM**

We claim the ornamental design for an actuator, as shown and described.

DESCRIPTION

FIG. 1 is a front top perspective view of an actuator; FIG. 2 is a front bottom perspective view of the claimed design of FIG. 1; FIG. 3 is a rear view of the claimed design of FIG. 1; FIG. 4 is a front view of the claimed design of FIG. 1; FIG. 5 is a left side view of the claimed design of FIG. 1; FIG. 6 is a right side view of the claimed design of FIG. 1; FIG. 7 is a top view of the claimed design of FIG. 1; and, FIG. 8 is a bottom view of the claimed design of FIG. 1. Any portion of the article depicted in broken lines forms no part of the claimed design. Broken lines formed by equal length dashes show unclaimed portions of the design. Broken lines formed of unequal length dashes (i.e., dash-dot) show boundaries between claimed and unclaimed portions of the design. Any portion of the article depicted in stippling indicates a contrasting color with respect to the adjacent portions of the article.
